UNITED STATES PATENT OFFICE

ABRAHAM VANDER HENST, OF GRAND RAPIDS, MICHIGAN, ASSIGNOR TO W. B. JARVIS
CO., A CORPORATION OF MICHIGAN

DOORLATCH

Application filed June 15, 1928. Serial No. 285,512.

This invention relates to door latches and particularly to a type thereof that may be locked against withdrawal of the bolt, the principal object being the provision of a new and novel type thereof that is simple in construction and economical to manufacture.

Another object is to provide a door latch with key controlled means whereby the handle may be rendered inoperative for withdrawal of the latch bolt when placed in locked position.

Another object is to provide a door latch having a rotatable shaft for causing withdrawal of the latch bolt, a handle being provided with means for locking it to the shaft whereby it may be operated to cause withdrawal of the bolt, such means permitting the handle to be rotatably disconnected from the shaft whereby it may be rotated without causing movement of the bolt and thereby place the latch mechanism in locked position.

Another object is to provide a door latch provided with an exterior sleeve formed to increase the strength of the door handle.

Another object is to provide means for locking an escutcheon plate against rotation.

A further object is to provide a new and novel means for preventing withdrawal of the door handle from a door.

The above being among the objects of the present invention, the same consists in certain features of construction and combinations of parts to be hereinafter described with reference to the accompanying drawing, and then claimed, having the above and other objects in view.

In the accompanying drawing which illustrates suitable embodiments of the present invention, and in which like numerals refer to like parts throughout the several different views,

Fig. 1 is a partially broken sectional view taken through the axis of a locking door handle shown mounted upon a door in connection with the door latch.

Fig. 2 is a sectional view taken on the line 2—2 of Fig. 1.

Fig. 3 is a sectional view taken on the line 3—3 of Fig. 1.

Fig. 4 is a face view of the member employed for locking the handle against withdrawal.

Fig. 5 is a sectional view of the door handle taken on the line 5—5 of Fig. 1.

Fig. 6 is a face view of the door panel showing the opening therein through which the door handle projects.

Fig. 7 is a view similar to Fig. 1 showing a modification of the handle locking mechanism.

Fig. 8 is a sectional view taken on the line 8—8 of Fig. 7.

Fig. 9 is a sectional view taken on the line 9—9 of Fig. 7.

Fig. 10 is a fragmentary sectional view showing a modified construction for holding the handle in place on the door.

In door latches for automobiles provided with means for locking the same against operation from the outside, the construction has heretofore been, as far as I am aware, such that the latch handle when the latch is locked, is locked against movement. The result is that thieves in attempting to open the door, often put sufficient force on the handle in attempting to turn it, to either break the locking means or else break off the handle. In either case, the result is liable to be relatively disastrous to the owner of the car.

By the use of the present invention I provide a means of eliminating such results and at the same time provide means for locking the door latch against operation that is simple and economical to manufacture and efficient in operation.

As illustrated in Fig. 1 the door may comprise an outer panel 15, and an inner panel 16 the margin of which is bent at an angle 90 thereto and secured to the outer panel 15. The door latch may be of any conventional construction, as that shown, which comprises a face plate 17 and a housing 18 between which is slidably received a latch bolt 19 which normally projects out through the marginal flange of the back plate 16 so as to be able to engage a suitable striker plate on a body pillar (not shown). The bolt 19 extends rearwardly as at 20 and is provided

55

with one or more lugs 21 against which a roll-back 22 is adapted to bear, the bolt 19 being urged outwardly of the door, and the lugs 21 into contact with the roll-back 22, 5 by means of a coil spring such as 23 or other suitable means. The roll-back 22 is secured against rotation to a rotatable shaft 24, the shaft 24 preferably being of a square section as in conventional constructions and 10 projecting out through an opening such as 25 in the outer panel 15.

In accordance with the present invention, 15 that part of the shaft 24 beyond the outer panel 15 is slightly enlarged as at 26 and is circular in section. The handle proper comprises a hollow or shell-like stem portion 27 which is rotatably received on the enlarged portion 26 and has its inner end turned over the same as at 28 to prevent withdrawal outwardly from it. The outer end of the shell 27 is turned outwardly to provide a pair of laterally extending flange portions 29, as indicated in Fig. 5, each of which is recessed as 20 at 30 and about and into which the metal 31 is cast to complete the handle. The outer end of the cylindrical portion 26 terminates intermediate the ends of the shell 27 and its outer end face is slotted as at 32. Slidably received within the slot 32 is a lock member 33 provided with a notch or groove 34 between its ends. The shell 27 is provided with an 25 opening 35 which may be brought into registry with the lock member 33 upon rotating the handle with the shell 27. A spring member 36 staked at its inner end in a groove 37 in the cylindrical end 26 bears against one end of the lock member 33 and constantly urges the lock member 33 into the opening 35. When the lock member 33 is in engagement 30 with the opening 35, the cylindrical end 26 of the shaft 24 is therefore locked to the shell 27 of the handle for equal rotation therewith. When it is desired to lock the latch bolt against withdrawal, means are provided for withdrawing the lock member 33 out of engagement with the opening 35 so that upon rotation of the handle, no rotation of the shaft 24 occurs, and consequently no movement of the latch bolt may take place. 40 This means is as follows: A key controlled lock cylinder 38 is inserted in the shell 27 from the outer face of the handle and provided with a pin 39 on its inner end which is offset from the axis of the lock and is 45 rotatable upon rotation of the key 40.

The pin 39 is received within the groove 34 and when the key 40 is rotated, the pin 39 is brought against the lower edge of the notch 34, as viewed in Fig. 1, and forces the lock member 33 downwardly against the pressure of the spring member 36 until the lock member 33 is retracted from the opening 35. This unlocks the handle from the shaft 24 so that the handle is free to turn on the shaft 24. When the key is withdrawn with

the lock in this position, it will be apparent that the latch is in locked position inasmuch as rotation of the handle causes no movement of the latch bolt.

When it is desired to place the handle in 70 locked position, the key is turned to move the pin 39 upwardly away from the lower wall of the notch 34, whereupon the spring 36 forces the locking member 33 outwardly, and, if the opening 35 is in alignment therewith, 75 into the opening 35 so as to lock the handle and shaft 24 together for equal rotation. Mis-alignment of the opening 35 and member 33 circularly of the handle will not prevent withdrawal of the key, as sufficient 80 clearance is provided in the notch 34 to permit the pin 39 to be moved to its extreme position, towards unlocked handle position, without necessitating the member 33 being projected into the opening 35. If such a 85 condition occurs, the spring 36 will snap the member 33 into the opening 35 as soon as the handle is turned sufficiently to bring the member 33 into alignment with the opening 35.

In order to prevent withdrawal of the locking cylinder 38, a circumferential groove 41 is formed in the surface of the locking cylinder 38 and a headed pin 42 projecting through the shell 27 and into the groove 41 95 is provided.

In lock cylinders of the type usually employed in connection with door handles, it is necessary to provide means for removing the key in either of two rotated positions representing the locked and unlocked positions respectively of the barrel. It is therefore necessary to provide one or more stops for bringing the lock barrel to rest in either of its key withdrawing or inserting positions so that the key may be readily withdrawn or inserted. In the present invention I employ the pin 42 and groove 41 for this purpose as well as preventing withdrawal of the lock barrel. This is accomplished in the following manner: The groove 41 extends substantially half-way around the surface of the lock barrel and the pin 42 is so positioned with relation thereto that when the barrel is rotated in either direction until stopped by the pin 42 contacting against the end wall of the groove, the barrel is in key removing or inserting position. The type of lock cylinder or lock barrel employed is immaterial, but that shown in the drawing is of that type 100 having tumblers 53 which project out past the surface of the barrel when the key is withdrawn. Slots 54 and 55 formed in the shell 27 permit the projection of the tumblers 53 when the key is removed, the slots 54 and 55 105 co-acting with the tumblers when the key is withdrawn to lock the barrel against rotation relative to the shell 27 in either locked or unlocked position as the case may be.

The pin 42 is prevented from withdrawal 110

by means of a shell 43 which surrounds the shell 27 and extends from the member 29 of the handle to a point adjacent the inner end of the shell 27. The shell 43 is preferably made to turn with the handle in any conventional manner such as by a projection 52 formed on the shell 43 engaging a suitable groove in the metal 31 of the handle. The shell 43 is preferably formed with a shoulder 44 against which the escutcheon plate 50 is adapted to bear when the mechanism is mounted upon the door.

The entire mechanism may be prevented from withdrawal from the door in the following manner: A spider member 45 shown in Fig. 4, having a plurality of outwardly extending bent arms 46 is slipped over the shaft 24, with the ends of the arms 46 extending through the opening 25. The arms 46 are each provided with an outwardly extending shoulder 47 which bears against the inner face of the panel 15. When the parts are assembled in this position, a washer 58 is placed back of the spider 45 and the shaft 24 is preferably staked as at 48 so as to prevent withdrawal of the washer 58 and spider 45 therefrom. By this means any attempt to pull the handle out of the door is effectively prevented, the ends of the arms 46 in projecting through the opening 25 preventing spreading of the arms 46, as will readily be apparent.

It is also preferable to provide a coil spring such as 49 between the escutcheon plate 50 and the spider 45 about the shell 43 in order to constantly urge the shoulder 44 against the escutcheon plate and thereby prevent rattling of the parts should there be any looseness present.

The escutcheon plate 50 is secured to the panel 15 by screws 80. Where, however, the escutcheon plate is circular in plan view and is not secured to the panel 15, as indicated in Fig. 10, in order to prevent possible rotation of the same relative to the panel 15 in such case, the opening in the panel 15 is formed as indicated at 81 in Fig. 6, with notches 59 in which the arms 46 seat so as to lock the spider member 45 against rotation. The escutcheon plate 82 is provided with one or more arms 60 on its inner face which extend inwardly and are received between the ends of two adjacent spider arms 46, thereby locking the escutcheon plate 82 against rotation. The arms 60 may be formed as shown or may be formed as an integral part of the escutcheon plate during the stamping process. Where the escutcheon plate is not secured to the panel 15 as thus described, the spring 49 may be replaced by another spring such as 83 held under compression between the inner face of the panel 15 and a washer 84 of larger diameter that replaces the washer 58, to constantly urge the mechanism inwardly of the panel 15.

In Fig. 7 I show a slightly modified con-

struction. In that figure the shaft 24 is not provided with an integral end portion as in Fig. 1, but is instead provided with a separate head member 90 which is non-rotatably secured thereto by any suitable means, that shown comprising indentations 61 formed in the edge of the shaft 24 and into which portions of the metal of the head 90 are staked to prevent withdrawal of the shaft 24. The construction of the locking member in Fig. 7 is modified from that shown in Fig. 1. In Fig. 7 the locking member is received within a groove 62 formed in the head 90. The locking member 63 in this case is elongated axially of the head 90 and is pivoted in the groove as at 64. It is further provided with a tongue 65 which is constantly urged into projected position within the slot 35 by a coil spring 66 held under compression between the locking member 63 and the bottom of the groove 62. A further difference in the construction shown in Fig. 7 is that instead of forming the pin on the lock barrel 38, a pin 68 is formed on the locking member 63 and the inner end of the lock barrel 38 is provided with a plate member 69 which, in turn, is provided with an eccentric opening 70 in which the pin 68 is received. The plate member 69 may be secured to the barrel 38 by providing marginal legs 71 which may be cast into the lock barrel 38 during the process of manufacture. The result, in this case, is exactly the same as that described in connection with Fig. 1. Upon rotation of the key 40, the lock barrel 38 is caused to rotate carrying with it the plate 69. As the plate 69 rotates, the edges of the opening 70 bears against the pin 68 on the locking member 63 and forces the tongue 65 out of engagement with the opening 35, thus unlocking the handle from the shaft 24 and placing the latch in free handle or locked position. If the key 40 is now turned back in the opposite direction, the spring 66 will force the tongue 65 out against the shell 27 until the handle is turned to bring the tongue 65 into registry with the opening 35, at which time the tongue will move into the opening 35 and will again lock the handle to the shaft 24 for equal rotation therewith.

In Fig. 7 a modified form of outer sleeve and escutcheon plate is shown. The outer sleeve 67 terminates at the escutcheon plate 72 and a cup-shaped washer 73 is received about the shell 27 within the escutcheon plate 72. A second cup-shaped washer 74 is staked to the shaft 24 in opposing relationship with respect to the washer 73 and a coil spring 75 is held under compression about the sleeve 27 within the washers 73 and 74, thus drawing the sleeve 67 firmly against the escutcheon plate 72 and preventing possible rattling between the various parts because of possible looseness that may be present between them.

Formal changes may be made in the spe-

specific embodiment of the invention described without departing from the spirit or substance of the broad invention, the scope of which is commensurate with the appended 5 claims.

What I claim is:

1. In combination, a rotatable shaft provided with an enlargement on one end thereof forming a shoulder, and a door handle 10 provided with a hollow stem rotatably received on said enlargement and enveloping the same, the free end of said stem being turned over at said shoulder to prevent said shaft from being withdrawn from said stem 15 in that direction.
2. In combination, a rotatable shaft, a handle provided with a stem rotatable on said shaft, a sleeve enveloping said stem, a shoulder formed on said sleeve intermediate its 20 ends, an escutcheon plate surrounding said sleeve, and means urging said shoulder against said escutcheon plate.
3. In combination with a door panel provided with an opening therein, a shaft projecting through said opening, means limiting movement of said shaft inwardly of said panel, a member secured to said shaft inwardly of said panel against movement in one direction thereon, said member provided 25 with fingers projecting through said opening, and shoulders on said fingers bearing against the inner face of said panel.
4. In combination with a door panel provided with an opening therein having a notch 30 in the side walls thereof, a shaft projecting through said opening, means limiting movement of said shaft inwardly of said panel, a member rotatably received on said shaft inwardly of said panel and prevented from 35 movement inwardly of said panel thereon, fingers on said member extending through said opening and one of which is received in said notch, and shoulders on said fingers bearing against the inner face of said panel.
5. In combination with a door panel provided with an opening therein having a notch in the side walls thereof, a door handle provided with a shaft extending through said opening, an escutcheon plate on the exterior 40 of said panel surrounding said handle for limiting movement of said shaft inwardly of said panel, a member rotatably mounted on said shaft inwardly of said panel and secured against inward movement on said shaft, portions 45 of said member extending through said opening, a shoulder on said member bearing against the inner face of said panel, an arm on said member engaging said notch for preventing rotation of said member relative to said panel and a finger on said escutcheon plate engaging said member to thereby lock said escutcheon plate against rotation relative to said member.
6. In combination, a door handle provided 50 with a hollow stem inwardly flanged at its

inner end, a shaft having an enlarged end rotatably received in said stem and a smaller end projecting through the inner end of said stem, a shoulder formed between said enlarged end and said smaller end and abutting 70 against said inwardly flanged end of said stem, a lock barrel received in the open end of said stem, means extending through said stem and engaging said lock barrel for preventing withdrawal thereof, and a sleeve surrounding said stem and concealing said means and maintaining said means in operative position.

7. In combination, a door handle provided with a hollow stem inwardly flanged at its 80 inner end, a shaft having an enlarged end rotatably received in said stem and a smaller end projecting through the inner end of said stem, a shoulder formed between said enlarged end and said smaller end and abutting 85 against said inwardly flanged end of said stem, a lock barrel received in the open end of said stem, means extending through said stem and engaging said lock barrel for preventing withdrawal thereof, a sleeve surrounding said stem and concealing said means and maintaining said means in operative position, and means controlled by said lock barrel for releasably locking said shaft to 90 said stem.

8. In combination, a handle having a hollow stem opening outwardly through said handle, the inner end of said stem being inwardly bent to form a radial shoulder, a headed shaft rotatably received in said stem 100 and projecting axially from the inner end thereof with its head received against said shoulder to limit its axial movement inwardly of said stem, a lock barrel received in the outer end of said stem, means projecting through said stem and engaging said lock barrel for preventing withdrawal thereof, said handle being provided with a recess on its inner side around said stem, a sleeve surrounding said stem and received in said recess, said sleeve preventing withdrawal of said means, an escutcheon plate surrounding said stem, and spring means constantly urging said plate against said sleeve whereby to urge said sleeve against said handle.

9. In combination, a handle having a hollow stem, a rotatable shaft received within said stem and projecting axially therefrom in one direction, means for limiting said shaft against axial movement relative to said sleeve in one direction, a lock barrel received in said stem and limiting said shaft against movement relative to said stem in the opposite direction, a diametrical slot in said shaft within said stem, an axially extending slot in said shaft connecting with said diametrical slot, an aperture in a side wall of said stem, a locking member slidable in said diametrical slot, an elongated spring secured within said axially extending slot and constantly urging 125

said locking member towards engagement with said aperture, and means co-operating between said lock barrel and said locking member for controlling the position of said locking member in said diametrical slot.

10. In combination, a handle having a stem, an escutcheon plate rotatably mounted on said stem, a sleeve surrounding said stem between said handle and said escutcheon plate, and spring means acting to clamp said sleeve axially between said handle and said escutcheon plate.

11. In a device of the type described, a handle having a tubular stem provided with a lateral aperture, a shaft rotatably received in said stem, a locking member non-rotatable relative to said shaft but movable transversely thereof, a spring constantly urging said locking member in one direction whereby to project it into said aperture when in alignment therewith, said locking member having a notch therein, a lock barrel carried by said stem, and a pin on said barrel received in said notch and adapted to engage a wall thereof to move said locking member in opposition to said spring, said notch having sufficient clearance to permit said lock barrel to move said pin to full unlocked handle position prior to projection of said locking member into said aperture.

12. In a device of the type described, a handle having a tubular stem provided with a lateral aperture, a shaft rotatably received in said stem, a locking member non-rotatable relative to said shaft but movable transversely thereof, spring means constantly urging said locking member in one direction whereby to project it into said aperture when in alignment therewith, a lock barrel member carried by said stem, one of said members being provided with a notch therein and the other of said members being provided with a pin, said pin and the walls of said notch being co-operable upon rotation of said lock barrel member to move said locking member in opposition to said spring, and said pin having sufficient clearance in said notch to permit said lock barrel to be moved to full unlocked handle position prior to projection of said locking member into said aperture.

13. A control handle for latches and the like having, in combination with a rotatable spindle, a sleeve open at one end and having a flange defining an opening in the other end, a barrel lock rotatably mounted in said open end and having key controlled means for securing the lock against rotation within said sleeve, a head rigid with said spindle and disposed within said sleeve between said lock and said flange, and a slide arranged for movement transversely of said sleeve and head in the rotation of said lock whereby to connect or disconnect said sleeve and head for relative rotation.

14. A control handle for latches and the

like having, in combination with a rotatable spindle, a cylindrical sleeve having an in-turned flange at one end, a barrel lock adapted to be inserted into the open end of said sleeve whereby to close such end, a head 70 formed on one end of said spindle and adapted to be journaled in said sleeve, the other end of said spindle being constructed to be inserted through the open end of said sleeve and to pass through the opening defined by 75 said flange whereby to bring said head into abutment with said flange prior to the insertion of said lock, and a locking member mounted for movement transversely of said sleeve and preventing axial movement of said head away from said flange, and means actuated by rotation of said barrel lock and controlling the position of said member to prevent relative angular movement between said sleeve and said head or to free said sleeve for rotation about the head.
